MOSES BENMOSCHE, OF NASHUA, NEW HAMPSHIRE, AND RICHARD P. ELLIOTT, OF BOSTON, MASSACHUSETTS.

HYPODERMIC SYRINGE.

1,144,343.

Specification of Letters Patent. Patented June 29, 1915.

Application filed August 22, 1913. Serial No. 786,119.

To all whom it may concern:

Be it known that we, MOSES BENMOSCHE, of Nashua, county of Hillsboro, and State of New Hampshire, and RICHARD P. ELLIOTT, of Boston, county of Suffolk, and State of Massachusetts, citizens of the United States, have invented certain new and useful Improvements in Hypodermic Syringes, of which the following is a specification, reference being had to the drawings accompanying the same and forming a part thereof.

Our invention relates to a hypodermic syringe wherein the pressure creating means and the fluid container are separate, and whereby different fluid containers may be inserted and removed after they have been emptied of their contents.

The objects of our invention are to produce a hypodermic syringe having a pressure creating chamber and a holder arranged to have a fluid containing chamber removably secured therein so as to form an air-tight joint at the ends of said container.

A further object of our invention is to so construct and arrange the holder and connecting pressure chamber as to use a fluid container in said hypodermic syringe, which container is provided with puncturable non-leakable closures at its ends, and means for puncturing said non-leakable closures after the container is inserted in the holder so that the fluid contained therein may be expelled from said fluid-container by pressure created in the chamber.

In the drawings forming a part of this specification—Figure 1 is a longitudinal sectional view of the syringe with a fluid container tube inserted therein in operative position; Fig. 2 is a cross section of the fluid container 2 and the body of the hypodermic syringe in which the fluid container tube is inserted for use; Fig. 3 is a longitudinal section of that portion of the hypodermic syringe designed to receive the fluid container 3; Fig. 4 is one of the fluid container tubes with the closures removed; Fig. 5 is one of the fluid container tubes with the closures in place; and Fig. 6 is one of the fluid container tubes showing both closures punctured so that any fluid contained therein may be driven out.

The hypodermic syringe consists of the holder 1 which is constructed with an open-

ing 2 through which the fluid container 3 may be inserted. Preferably we may employ positioning strips 4, 4, formed of a part of the portion 1. These strips 4, 4, may be bent inward as shown in Fig. 1 so that when the fluid container 3 rests against them it will be centralized between the openings of the syringe. The lower end of the tube 1 is closed by a plug 5 secured therein. The plug 5 is provided with a tapering upwardly projecting puncturing point 6 having a hole therethrough designed to puncture one end of the closure on the fluid container 3. The lower end of the plug 5 may be provided with a projection 7 externally threaded to receive the cap 8. The cap 8 is designed to contain a sterilizing fluid, such as formaldehyde designed to keep the needle 9 sterile and free from bacteria. The use of the cap 8 is optional. This needle 9 has a portion 10 which is contracted at 11 and may be threaded to screw into a threaded hole in the lower end of the plug 5. The needle may be secured to the syringe in any other suitable manner. The plug 5 has a recess designed to receive the washer 12 against which the lower end of the fluid container 3 may be pressed to form a non-leakable closure. The upper end of the holder portion 1 has secured in it a plug 13 having a threaded hole 14 therethrough so that the threaded end 15 of the syringe 16 may be screwed therein. The syringe 16 has the tapering puncturing point 17 designed to pass through the plug 13 and contact with whichever of the puncturable closures 18, 19, is presented to it and puncture the same so that the air pressure created in the barrel 19 of the hypodermic syringe 16 will pass through the hole 20 to expel fluid from the body 21 of the fluid container 3. A washer of flexible material 23 surrounds the end 17 so as to contact with the end of the fluid container 3 to make a non-leakable joint.

The barrel 19 has inserted therein a plunger 24 secured to the end of the stem 25, which stem is provided with a button 26 which serves to form a surface for the thumb or finger of the operator to press down the plunger 24 to create pressure in the barrel 19. The stem 25 of the plunger passes through a cap 27 which may be threaded upon the barrel 19 of the syringe. A spiral

spring 28 is provided, and which surrounds the rod 25, its lower end pressing upon the cap 27 and its upper end underneath the button 26. This spring 28 serves to keep 5 the plunger 24 in an upward position and the barrel 19 filled with air.

The operation of our hypodermic syringe is as follows:—When it is desired to inject a fluid solution into the tissues of a human 10 or animal body, the barrel 16, and its threaded portion 15 is turned to screw it outwardly from the plug 13 so that the fluid container 3 may be inserted between the ends 6 and 17 of the syringe. Thereafter, the barrel 16 15 is turned to screw the portion 15 inwardly or downwardly until the ends 6 and 17 puncture the puncturable closures 18, 18, on the ends of the fluid container 3, firmly pressing the ends of the fluid container upon 20 the washers 12 and 23 to form a non-leakable joint. When the fluid container is inserted as described, the plunger 24 will be held by the spring 28 in its extreme upward position. In Fig. 1 it is shown partially moved 25 to its extreme upward position. As above described, the syringe is ready to be used, except that the tube 8 must be unscrewed from its threaded connection 7 to expose the hollow needle 9. As before stated, this tube 30 8 contains fluid or cotton saturated with a sterilized solution, such as formaldehyde or alcohol. When the tube 8 is removed the syringe is ready for the operation of injecting a fluid solution into the tissues of a 35 human or animal body. By pressing downwardly upon the button 26 the plunger 24 is moved downwardly and pressure created upon the top of the liquid contained in the liquid container 3, thus forcibly expelling 40 the liquid by means of the needle 9 into the tissues before mentioned. In constructing the syringe, we preferably arrange the barrel 19 so that its air capacity is slightly less than the fluid capacity of the fluid container 45 3 so that all the fluid may not be expelled from said fluid container 3 by the action of the plunger 24. This prevents the air in the barrel 19 from being injected into the tissues and also prevents it from coming 50 into contact with the walls of the hole in the plug 5 of the needle 9, so that said walls may be kept sterile so far as any contamination to them may take place from the air in the barrel 19. When the operation of injecting 55 the fluid from a fluid container 3 has been completed and it is desired to inject another solution, the barrel 16 and the threaded portion 15 are screwed upwardly until the points 6 and 17 have space enough between 60 them to be of greater distance than the length of the body of the fluid container 3, whereupon said empty container 3 may be pushed out and a fresh container inserted therein.

65 The syringe may be used in the ordinary

way when an empty fluid container is in place, as the plunger 24 may be moved inward to expel the air in the syringe and the needle inserted in a fluid and the fluid drawn into the needle and fluid container 70 by suction induced by moving the plunger 24 outward, and the fluid thereafter expelled by moving the plunger 24 inward. Furthermore, fluid containers may be provided with non-leakable, puncturable closures 75 at one end only so that fluids may be put in the containers by the operator as and when desired, and the fluid containers inserted in the syringe holder when it is in a vertical position, as shown in Fig. 1, or the 80 reverse of said position and the closure punctured by whichever of the points 6 or 17 that comes in contact with it when the part 15 is screwed inward.

We do not confine ourselves to the exact 85 form of the parts shown herein, as the sizes and shape of the parts may be varied to suit the convenience or requirements of the user, without departing from the spirit of our invention. Likewise, sliding fits or 90 cam movements may be substituted for the screw threaded parts without departing from our invention.

What we claim is—

1. In a hypodermic syringe, the combination of a holder; fluid containers which have a plurality of puncturable closures adapted to be removably held by said holder; means for puncturing the puncturable closures after the fluid container is inserted in the 100 holder; and a pressure creating chamber connected to the holder. 95

2. In a hypodermic syringe, the combination of a holder arranged to removably hold fluid containers which have a plurality of 105 puncturable closures adapted to be removably held by said holder; means for puncturing the puncturable closures after the fluid container is inserted and while it is being secured in the holder; a pressure creating chamber at one end of said holder; and a hollow needle at the other. 110

3. In a hypodermic syringe, the combination of a holder for removably holding fluid containers which have a plurality of 115 puncturable closures; means for puncturing said closures; a pressure-creating chamber removably secured to one end of said holder, and a hollow needle secured to the other end of said holder, the pressure-creating chamber and needle being so arranged that pressure created in the pressure-chamber will force liquid in the containers outwardly through the needle. 120

4. A device for injecting fluids into human or animal tissues, comprising a holder; a pressure creating chamber adjustably secured to one end of said holder; a hollow needle removably secured to the other end of said holder; a fluid-container having 125

puncturable non-leakable closures secured to its ends, said fluid-container and holder arranged so the fluid-container can be removably secured in the holder; and means for puncturing the closures to the fluid-container after it is inserted in the holder.

5. In a hypodermic syringe, the combination of a holder for removably holding fluid-containers which have puncturable closures; 10 means for removably securing a hypodermic needle to one end of said holder; means for adjustably securing a pressure creating chamber to the other end of said holder; and means for puncturing said closures after

15 a container is inserted in the holder.

6. In a hypodermic syringe, the combination of a holder for removably holding fluid-containers; means for removably securing a hypodermic needle to one end of said 20 holder; means for adjustably securing a pressure-creating chamber to the other end of said holder; and means connected to said holder for puncturing the puncturable clo-

sures of fluid-containers when said containers are placed in the holder.

7. The combination of a hypodermic syringe having means for removably holding containers therein filled with sterile fluids and means for puncturing both the closures to said fluid containers after they 25 are inserted in the syringe; a hollow needle; a compression chamber; a plunger; a spring for normally holding the plunger in position to be operative; with fluid containers having puncturable fluid-tight closures covering the 30 openings thereof; and said puncturable closures.

In testimony whereof, we have hereunto set our hands, in the presence of two subscribing witnesses, this the 21st day of 40 August, A. D. 1913.

MOSES BENMOSCHE.
